UNITED STATES PATENT OFFICE.

FRANK H. ALBER, OF DRISCOLL, NORTH DAKOTA.

DRAFT-EQUALIZER.

1,110,279.

Specification of Letters Patent.

Patented Sept. 8, 1914.

Application filed March 9, 1914. Serial No. 823,554.

To all whom it may concern:

Be it known that I, FRANK H. ALBER, a citizen of the United States, residing at Driscoll, in the county of Burleigh and State of North Dakota, have invented certain new and useful Improvements in Draft-Equalizers, of which the following is a specification, reference being had to the accompanying drawings.

10 This invention relates to certain improvements in draft equalizers and has relation more particularly to a device of this general character adapted to be used in connection with a pole team and a lead team; and the 15 object of the invention is to provide a device of this general character having novel and improved means whereby the pulling strain imposed by the two teams will be so conveyed to the vehicle as to assure such vehicle traveling in the proper direction.

The invention consists in the details of construction and in the combination and arrangement of the several parts of my improved draft equalizer whereby certain important advantages are attained and the device is rendered simpler, less expensive and otherwise more convenient and advantageous for use, all as will be hereinafter more fully set forth.

30 The novel features of the invention will be defined in the appended claims.

In order that my invention may be the better understood, I will now proceed to describe the same with reference to the accompanying drawings, wherein—

Figure 1 is a view in top plan of the draft rigging containing equalizing means constructed in accordance with the embodiment of my invention; Fig. 2 is a view partly in side elevation and partly in section of the device as disclosed in Fig. 1, and Fig. 3 is a sectional view taken substantially on the line 3—3 of Fig. 2.

As disclosed in the accompanying drawings, 1 denotes the draft pole which may be of any ordinary or preferred construction and is provided at its rear end with a pronged head 2 which is adapted to be operatively engaged with the vehicle proper in a convenient manner. Pivots connected as at 3 to the opposite sides of the draft pole 1 and adjacent the rear extremity thereof are vertically disposed equalizing levers 4 projecting above and below the draft pole 1. 55 Between the opposite extremities of the equalizing levers 4 are pivotally engaged as

at 5 the rigid linked members 6 directed rearwardly of the draft pole 1 and having their free extremities accommodated within the longitudinally directed linked grooves or channels 8 afforded in the upper and lower faces of the draft pole 1 and maintained in operative positions therein through the medium of the transverse pins 9 suitably directed through the free extremities and adapted to project beneath the retaining or guide straps 10. The rigid links 6 constitute pull members and serve effectively to give the lead team and the pole team a straight pull at all times and the uppermost 70 of such links is provided adjacent its lower extremity with the forwardly directed clevis 11 to which is suitably engaged as at 14 the linked rod 15 having its forward extremity suitably connected as at 17 with the sliding 75 member 18, the opposite extremities of such sliding member 18 being directed through the guide loops 19 projecting upwardly from the draft pole 1. This member 18 is provided with a clevis 20 whereby the draft rigging 80 of the pole team may be readily and conveniently applied in operative position. The under rigid link 6 has also rigidly engaged therewith adjacent its free extremity the clevis 21 having engaged therewith the 85 linked rod 23 the outer or free extremity whereof having engaged therewith as at 24 an extremity of a flexible member 25, herein disclosed as a linked chain, the opposite extremity of such member 25 being provided 90 with the engaging means 26 herein shown as a hook whereby the draft rigging of a lead team may be connected with convenience and facility.

In order that the requisite pull may be 95 put upon the rod 23 I find it of advantage to direct the flexible member 25 through the loop member 27 depending from the loop member 28 rigidly connected with the forward end of the draft pole 1. When the use 100 of a lead team is dispensed with, the flexible member 25 is adapted to be threaded through the loop 28 and have its hook 26 engaged with one of the links of the member 25 rearwardly of the loop 28 whereby it will be seen 105 that the ordinary pole team may be employed with convenience and facility.

From the foregoing description, it is thought to be obvious that a draft equalizer constructed in accordance with the embodiments of my invention is of an extremely simple and operatively inexpensive nature

and is particularly well adapted for use by reason of the facility and convenience with which the various parts thereof may be assembled and the efficaciousness with which it performs its various functions, and it will also be obvious that my invention is susceptible of some change and modification without material departure from the principle and spirit thereof and for this reason I 10 do not wish to be understood as limiting myself to the precise arrangement and formation of the several parts herein shown in carrying out my invention except as defined by the appended claims.

15 Having thus described my invention what I claim is:

1. In combination with a draft pole, of vertically disposed levers pivotally connected to such pole and projecting above and below the same, rearwardly directed rigid links pivotally mounted between the opposite extremities of the lever and having their free extremities contacting with the adjacent faces of the pole, such faces of the pole 20 being provided with longitudinally disposed grooves to receive the free extremities of the links, longitudinally directed parallel guide straps carried by such faces of the draft pole at opposite sides of the grooves, pins disposed transversely through the free extremities of the rigid links and disposed between the draft pole and the guide straps, a sliding clevis mounted upon one face of the pole, a connection between such sliding clevis and 25 one of the links, a rod operatively connected with the second link and provided with engaging means, and coacting means carried by the rod and the pole serving to hold the sliding clevis against movement in one direction.

2. In combination with a draft pole, of vertically disposed levers pivotally connected to such pole and projecting above and below the same, rearwardly directed rigid links pivotally mounted between the opposite extremities of the lever and having their free extremities contacting with the adjacent faces of the pole, such faces of the pole being provided with longitudinally disposed grooves to receive the free extremities of the links, longitudinally directed parallel guide straps carried by such faces of the draft pole at opposite sides of the grooves, pins disposed transversely through the free extremities of the rigid links and disposed between the draft pole and the guide straps, a sliding clevis mounted upon one face of the pole, a connection between such sliding clevis and 30 one of the links, a rod operatively connected with the second link and provided with engaging means.

2. In combination with a draft pole, of vertically disposed levers pivotally connected to such pole and projecting above and below the same, rearwardly directed rigid links pivotally mounted between the opposite extremities of the lever and having their free extremities contacting with the adjacent faces of the pole, such faces of the pole being provided with longitudinally disposed grooves to receive the free extremities of the links, longitudinally directed parallel guide straps carried by such faces of the draft pole at opposite sides of the grooves, pins disposed transversely through the free extremities of the rigid links and disposed between the draft pole and the guide straps, a sliding clevis mounted upon one face of the pole, a connection between such sliding clevis and 35 one of the links, a rod operatively connected with the second link and provided with engaging means, and coacting means carried by the rod and the pole serving to hold the sliding clevis against movement in one direction.

In testimony whereof I hereunto affix my signature in the presence of two witnesses.

FRANK H. ALBER.
